CLAIM

The ornamental design for a jewelry bar, as shown and described.

DESCRIPTION

FIG. 1 is a perspective view of a jewelry bar showing my new design.

FIG. 2 is a front elevation view of FIG. 1.

FIG. 3 is a right end elevation view of FIG. 2, the left end elevation view being a mirror image.

FIG. 4 is a top plan view of FIG. 2; and,

FIG. 5 is a bottom plan view of FIG. 2.

The broken lines showing jewelry and attachment screws in FIG. 1 are for environmental purposes only and form no part of the claimed design.
